[57] CLAIM

The ornamental design for a caddy for use on a walker,
as shown and described.

DESCRIPTION

FIG. 1 is a front, top and side perspective view of the
caddy for use on a walker showing my new design;
FIG. 2 is a front elevational view thereof, the rear being
a mirror image of the front shown in FIG. 2;

FIG. 3 is an end elevational view thereof, the end opposite
being a mirror image of the end shown in FIG. 3;
FIG. 4 is a top plan view thereof; and,
FIG. 5 is a bottom plan view thereof.

FIG. 1

FIG. 2

FIG. 3

FIG. 4

FIG. 5
